ILAR ARTICLE

Harold C. Johnson, Downey, Calif.

Application November 20, 1950, Serial No. 13,063

Term of patent 7 years

(Cl. D34—13)

To all whom it may concern:

Be it known that I, Harold C. Johnson, a citizen of the United States, residing in Downey, in the county of Los Angeles and State of California, have invented a new, original, and ornamental Design for a Combination Playing Card and Canasta Tray and Case or Similar Article, of which the following is a specification, reference being had to the accompanying drawing, forming a part thereof.

Fig. 1 is an end perspective view of a combination playing card and canasta tray and case or similar article, showing my new design with the tray telescoped within the confines of the case;

Fig. 2 is a perspective view of the opposite end thereof;

Fig. 3 is an exploded view thereof;

Fig. 4 is a perspective view of the opposite end of the case portion shown in Fig. 3;

Fig. 5 is an end view of the opposite end of the tray portion shown in Fig. 3;

Fig. 6 is a top plan view of the tray portion shown in Fig. 3; and

Fig. 7 is a side elevational view of the tray portion shown in Fig. 3.

I claim:

The ornamental design for a combination playing card and canasta tray and case or similar article, as shown.

HAROLD C. JOHNSON.
